SIGNALING SYSTEM.

1,024,446.

Specification of Letters Patent.

Patented Apr. 23, 1912.

Original application filed December 8, 1909, Serial No. 532,052. Divided and this application filed April 5, 1911. Serial No. 619,017.

To all whom it may concern:

Be it known that I, EDWIN R. GILL, residing at Yonkers, in the county of Westchester and State of New York, have invented certain new and useful Improvements in Signaling Systems, of which the following is a specification.

This invention relates to signaling systems, and more particularly to such systems as are adapted for telephonic train despatching; the present application being a division of an application filed by me December 8th, 1909, Serial No. 532,052, now Patent No. 1,020,975, issued March 26, 1912, selective 15 signaling systems.

One of the objects of the present invention is to provide a convenient method of communicating the correct time simultaneously to various despatchers along a telephone train despatching circuit.

Another object is to provide means whereby signals arranged in a telephonic despatching circuit may be operated in consonance with electrical impulses impressed 25 upon a telegraph circuit from the National Observatory or other sending station, thereby enabling the time piece of each despatcher to be periodically standardized.

Other objects will be in part obvious and 30 in part pointed out hereinafter.

The invention accordingly consists in the features of construction, combinations of elements and arrangements of parts, which will be exemplified in the construction hereinafter described, and the scope of the application of which will be indicated in the appended claims.

In the accompanying drawing, wherein is illustrated a preferred embodiment of my 40 invention, the figure is a diagrammatic view of a preferred form thereof.

Referring now to the drawing, the view may be said to illustrate diagrammatically the signaling apparatus, wiring, and signal 45 operating apparatus located in the principal train despatcher's station, as well as in certain receiving stations of a telephonic train despatcher's circuit, said stations being designated respectively A, B and C.

1 and 2, respectively, denote opposite sides 50 of a main telephone line, and connected in bridges thereof as indicated at 3, 4, and 5, are telephones, the receivers of which are

indicated at 6, 7 and 8. Calling devices for the various telephones along the line are 55 provided in each of the stations, said calling devices in the present instance comprising magnetos 10, 11 and 12, each magneto being located in a normally open bridge of the telephone line, said bridges being indicated 60 at 13, 14 and 15.

The signaling devices, and other operating mechanisms in each of the receiving stations being similar, but one set thereof need be described in order to impart a clear 65 understanding of the present invention. A description of the apparatus located in station B will accordingly be given. Leading from the wire 1 of the telephone line is a wire 16, which connects with one terminal 70 of the coil 17, positioned upon one leg of the magnet, the yoke of which is shown at 18, and leading from the other terminal of said coil is a wire 19. This wire leads to a terminal 20 of the selector illustrated diagrammatically at 21. This selector, which is preferably a structure, such as is described in Letters Patent No. 906,523, issued to me December 15, 1908, includes a magnet 22 and a coil 23 on said magnet, the latter being connected with the terminal 20. Magnet 22 is adapted to operate mechanism (not shown) which causes a contact member 24 to engage with opposed contact member 25 and close a local circuit 26. Included in 80 local circuit 26, in the present instance, is battery 27 and a signal 28 which signal may take the form of an ordinary electric call bell. Coil 23 is connected with the terminal 30 of the selector, and from this terminal leads a wire 31 to the terminal of the coil 32 positioned upon the other leg of magnet 18. From the opposite terminal of this coil 32 leads wire 33 to the opposite side 2 of the telephone line. It will thus be seen 90 that the coils 17 and 32 of the magnet 18, as well as the selector 21, are connected in bridge of the telephone line, and in series with each other. If desired, a portion of the local circuit 16, may include a coil 34, 100 positioned upon magnet 22, so that when local circuit 26 is closed by selector 21 an induced current will be set up in the main line, the effect of which will be a buzzing in the various telephone receivers along the 105 telephone line, when the local signal 28

is operated by the closure of the said local circuit. This buzzing, which constitutes an "answer back", will inform the operator that the local signal operating circuit has been closed by the operation of the selector.

35 denotes a polarized armature, which co-operates with the poles 36, 37 of the magnet 18. Armature 35 is provided with a clapper 38, which is adapted to co-act with the bells 40, 41 to sound the signal. In the present embodiment of my invention, the armature 35 is held in constant engagement with one of the poles of the magnet 18, in the present instance pole 36, as by means of 15 a spring 39, such construction constituting a "biased bell," well known in the art.

42 indicates a relay comprising coils 43 and an armature 44. The coils 43 of this relay are included in a local circuit 45, which 20 is provided with a battery 46, and included in this local circuit is a sender box 47, having operating keys 48. These keys, when operated, actuate mechanism (not shown), to impress impulses of a predetermined 25 character upon the local circuit 45, thereby operating the relay 42, the armature of which is connected as by means of a wire 49 with the wire 50 of the side 2 of the telephone line, an impedance coil as at 51 being 30 provided in this wire, and a condenser as at 52 being also provided therein between the sides 1 and 2 of the telephone line. The contact member 53 with which co-operates the armature 44 of the relay 42 is connected 35 by means of the wires 54 and 55 with the terminal 56 of the pole changer 57. Leading from the opposite pole 58 of the pole changer 57 is a wire 60, which extends to the side 1 of the telephone line and includes 40 the impedance coil 61. The pole changer 57 is also provided with terminals 62 and 63. A wire 64 shown in dotted lines connects terminals 56 and 63, and a wire 65 similarly connects the terminals 58 and 62.

45 66 indicates a swinging member comprising the arms 67 and 68, the point of pivotal connection of which is in electrical connection with the positive and negative sides, respectively, of the battery 70, as by means 50 of the wires 69 and 71. These points of pivotal connection of the arms 67 and 68 of the swinging member 66, which are herein shown at 72 and 72', are insulated from each other as will be understood.

55 The telegraph line comprises wires 73 and 74 and is connected with double switch arm 75, 76 joined as by means of a link 77, so that when it is desired to actuate the biased bells of the various receiving stations, the 60 swinging of the switch arms 75 and 76 to the position shown in the drawing will enable the impulses impressed upon the telegraph line to actuate the relay 42, thereby causing the battery 70 to impress impulses upon the 65 telephone line according to the following

circuit: Assuming the reversing switch member 66 to be in the position shown in the drawing; from battery 70, wire 71, terminal 72', switch arm 78, terminal 63, wire 64, wire 55, contact 53, armature 44, of the relay 42, wire 49, wire 50, thence through the impedance coil 51 to the side 2 of the telephone line, thence through wire 23, coil 32, wire 31, terminal 30 of the selector 21, coil 33 of the selector magnet, terminal 20, wire 19, coil 17, and wire 16 to the side 1 of the telephone line, thence through impedance coil 61, wire 60, terminal 58, wire 65, switch arm 67, wire 69, back to the battery 70. It will therefore be seen that when the switch arm 66 is in the position shown in the drawing, the system is put into such condition as will enable the various biased polarized signals along the line to be operated by the impulses impressed upon the telephone line by the battery 70, in accordance with the operation of the relay 42, which as above described, is operated by impulses impressed upon the telegraph line, the sides of which are indicated at 73 and 74. The impulses, which are sent over the telegraph line, are impressed thereon from the National Observatory at a predetermined time, the object of the invention as stated above being to enable the time pieces of the various operators along the line to be periodically standardized. When it is desired to set the system for selective signaling, the switch arm 66 is moved to enable arms 67 and 68 to engage 100 respectively with contacts 56 and 58. This reverses the poles of the battery 70 to the telephone line, and enables keys 48 of the sending apparatus 47 to operate the relay 42 in accordance with the particular series 105 of codal impulses sent out by the various keys. It will be understood of course that the switch arms 75 and 76 will be moved out of electrical engagement with the wires connecting them with the relay 42 when the system is set for selective signaling. The 110 impulses impressed upon the telephone line from the sending apparatus 47 will have no effect upon the armature of the various biased signaling devices in the various sending stations inasmuch as these armatures have been returned to the position shown in the drawing by means of the springs 39, after their actuation by the telegraphically 115 impressed impulses, and the polarity of the current has been reversed. These impulses will, however, operate the selective signaling apparatus at the particular station called, whereby the local signaling circuits, one of which is shown at 26, will be closed 120 and the signal therein actuated.

As many changes could be made in the above construction and many apparently widely different embodiments of this invention could be made without departing from 130

the scope thereof, it is intended that all matter contained in the above description or shown in the accompanying drawing shall be interpreted as illustrative and not in a limiting sense. It is also to be understood that the language used in the following claims is intended to cover all of the generic and specific features of the invention herein described and all statements of the scope of the invention, which as a matter of language, might be said to fall therebetween.

Having thus described my invention, what I claim as new and desire to secure by Letters Patent, is:

1. In a system of the class described, in combination with a telephone line, a biased signaling device connected in bridge of said line, a battery for applying a current to said line to operate said biased signal, a relay, and a telegraph line, the sides of which are adapted to be connected to said relay, whereby said biased bell may be operated in accordance with impulses impressed upon the telephone line from said telegraph line.

2. In a system of the class described, the combination of a telephone line including a sending station and a plurality of receiving stations, a selector, a biased signaling device connected in bridge of the line, at each of the various stations, a source of current supply, a relay for applying said source of current to the line, means for impressing selective signaling impulses upon the line connected with said relay, a telegraph line adapted to be connected with said relay, and to cause the same to impress impulses upon the line to actuate said biased signaling devices, and means for reversing the polarity of the source of current supplied to the telephone line.

3. In a system of the class described, the combination with a telephone line, of a selector and a biased signal connected in bridge of the line and in series with each other, a battery for supplying current to said line, and a telegraphically operated relay for applying said battery to the line.

4. The combination with a telephone line, of a selective signal operator and a biased signal connected in bridge of the line and in series with each other, a battery for supplying current to the line, a pole changer for reversing the polarity of said battery to the line, a relay adapted when operated to impress impulses upon the line, means connected with said relay for applying impulses upon the line to operate said selective signaling operator, and a telegraph line adapted to operate said relay to impress impulses upon the line to operate said biased signal.

5. The combination with a telephone line, of a selector and a biased signal connected in bridge of the line and in series with each other, a local circuit including a signal

adapted to be closed by the operation of said selector, a telegraph line, sending apparatus, a relay common to said telegraph line and said sending apparatus, a battery adapted to be applied to the line by said relay, and means for reversing the polarity of said battery to said line.

6. In a system of the class described, in combination with a line including a sending station and a plurality of receiving stations, a selector and a biased signal connected in bridge of the line in each of the various receiving stations, said selector and said biased signal being connected in series with each other, a local circuit including a local signal located in each station adapted to be closed by the operation of the selector therein, a battery, a pole changer for reversing the polarity of the battery to the line, a relay for applying said battery to said line to operate a selector in certain of said stations to the exclusion of others, or to operate the biased signals in all of said stations, the particular sets of apparatus operated being determined by the polarity of the battery with respect to the line, apparatus in the sending station for operating said relay to impress impulses upon the line to operate said selectors, and a telegraph line adapted to be connected to said relay and to cause the same to impress impulses from the battery upon the line and to operate said biased signals when the polarity of the battery to the line is reversed.

7. In a system of the class described, the combination with a line including a sending and a plurality of receiving stations, of a battery for supplying current to the line, a pole changer for reversing the polarity of the battery to the line, a relay for impressing impulses of different polarities to the line, a selector, a biased bell connected in bridge of the line in each of the various receiving stations, said selector and said biased bell being connected in series with each other, a local signal in each of the various stations, the operation of which is determined by the selector in that station, means in the sending station for operating said relay to cause the same to impress impulses of a determined polarity to the line to operate said selector, and a telegraph line connected with said relay, adapted when the polarity of said battery to the line is reversed to cause said relay to apply impulses from the battery to the line to operate said biased signals.

8. In a signaling system, in combination, a telephone line, a polarized signal in bridge of the telephone line, a battery adapted to be applied to the telephone line, a telegraph line, a relay actuated by impulses impressed upon the telegraph line adapted to apply said battery to said telephone line, and means independent of said relay for

changing the polarity of said battery with respect to said line.

9. In a signaling system, in combination, a telephone line, a signal comprising a bell connected in bridge of the telephone line, a selector in said bridge, a local circuit comprising a battery and a signal adapted to be closed by said selector, a battery, means for applying said battery to said telephone line 5 to operate the selector whereby said local circuit will be closed and said second mentioned signal operated, a telegraph line, a relay adapted to be actuated by impulses 10

impressed upon the telegraph line for applying said battery to said line, and means 15 independent of said relay for reversing the polarity of said battery with respect to said line whereby when said relay is operated said first mentioned signal will be operated.

In testimony whereof I have affixed my 20 signature in the presence of two witnesses.

EDWIN R. GILL.
